UNITED STATES PATENT OFFICE.

THOMAS F. BATES, OF SHELBYVILLE, TENNESSEE.

PROPHYLACTIC SCALER.

Application filed November 2, 1925. Serial No. 66,339.

The present invention relates to improvements in prophylactic scalers and has for an object to provide a dental instrument of an improved character by the use of which the processes of scaling and curetting may be carried forward with greater facility and convenience to the dentist and with better results in the patient.

A further object of the invention is to provide a scaler peculiarly constructed for the use of general practitioners, dental nurses and oral hygienists in the treatment of pyorrhea where the shallow pockets are found at the beginning of the disease.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a fragmentary perspective view of an instrument constructed according to the present invention.

Figure 2 is a similar view taken at another angle.

Figure 3 is a top plan view of the instrument, and

Figure 4 is a front elevation thereof.

Referring more particularly to the drawings, 5 designates generally the handle having the tapered shank 6 extending upwardly therefrom with the portion 7 extending diagonally thereto. This portion 7 carries the blade 8, the blade extending preferably at substantially right angles to the shank portion 7 with the wider tip end of the blade, which is flattened out at its extremity, extending approximately in the prolongation of the axis of the handle 5 to facilitate the working with the instrument and to resist the turning of the instrument in the hand of the dentist. The improved blade comprises the transverse cutting edge 9 at the extremity of the blade and at its wide portion. This cutting edge extends from side to side of the blade and is ground to appropriate sharpness.

The transverse cutting edge 9 is made on the curved tip portion 10 of the blade, such blade being substantially flattened from the point indicated at 11 in Figure 2 outwardly to the rounded or rolled tip portion 10. The flattening of the blade facilitates the formation and sharpness of the straight side cutting edges 12 and 13 and the rounded side cutting edges 14 and 15, which extend into the ends of the transverse cutting edge 9. The inner side of the curved tip 10 presents a concave surface suitable for lying about convexities in the teeth, tooth roots and the like, while the outer surface of the tip 10 forms a convex portion for entering cavities. The blade 12 is flattened very thin, so as to extend between the teeth and into small places and cavities. The outer surface or convex portion of the tip, besides being spread out or widened at the extremity thereof is provided with the rounded corner portions 16 and 17 to facilitate rocking of the blade from one lateral cutting surface to the other.

As indicated in Figures 3 and 4 the blade is also turned spirally about its long axis in order to strengthen the very thin blade thus made and to lie more uniformly about the convex surfaces of the teeth.

In the use of the instruments, such instruments will not be found particularly useful in the treatment of the deep pockets of "pyorrhea alveolaris" but rather the shallow pockets found at the beginning of the disease, and the instruments are very useful for scaling and curetting around the necks and crowns of the teeth. The instrument may go, but preferably only slightly, under the gum. Work of this character is not generally confined to pyorrhea specialists, and the instrument will be quite generally useful to general practitioners, dental nurses and oral hygienists. The corners 16 and 17 may be rounded by drawing the same through a semi-circular grooved sharpening stone. The straight cutting edge 9 at the tip of the scaler blade may be sharpened on a flat stone, as may the straight side cutting edges 12 and 13, as these edges lie in a straight line. The inner curved surface may be sharpened with a cylindrical stone of proper diameter and kept uniform. The straight edges of the end 9 and the sides 12 and 13 will plane on flat surface; the inner curved edges 14 and 15 will plane as concave blades on the convex surfaces of teeth and roots without slipping out of place.

The rounded corners will act as convex blades and plane in the depressions and concave surfaces of the teeth and roots. The inner portion of the blade being on the arc of a circle, allows the shank to evade the protuberances of the crowns, and the construc-

tion permits the operator, with a pull cut, to draw out the infectious débris instead of forcing it deeper in the uninfected area as push scalers will do. The blade, being in the form of an arc, will not pack full of the deposits removed, as will files and the ordinary hoe-shaped scalers, which have the blades bent off at right angles to the shanks.

The corners of the blades being rounded and there being no angles in any part of the cutting edges, they will not leave sharp, irritating angular scratches on the tooth surfaces nor produce unnecessary laceration of the surrounding soft tissues. The blades are thin in one aspect and may be easily passed in between crowded teeth and roots. These blades may also be used effectively as alveolar and bone curettes when the soft tissue is laid back in the more radical surgery. They become more delicate instruments as they are worn down uniformly by sharpening and can be used until quite worn out.

The instrument permits of simultaneous scaling and curetting by the adjoining and angularly disposed cutting edges 9, 14 and 15 and by reason of the rounded corners 16 and 17 and the convex outer side of the tip portion carrying all of these various blades, the instrument is permitted to rock by contact of its convex portion on the surface of the tooth or root treated, whereby the rounded cutting edges 14 and 15 may be successively brought into proper position for the work of scaling or curetting.

It is obvious that various changes and modifications may be made in the details of construction and design of the above specifically described embodiment of this invention without departing from the spirit thereof, such changes and modifications being restricted only by the scope of the following claims.

What is claimed is:--

1. A dental scaler and curette comprising a blade having a rounded relatively short ter-

50 minal tip portion with concave inner and convex outer side and with the corner portions rounded on the convex side, said tip portion having a transverse cutting edge at its extremity, and curved side cutting edges joining with the ends of said transverse cutting edge.

2. A dental scaler and curette comprising a blade having a flattened outer thin portion 55 with a rounded relatively short terminal tip, said flattened portion and tip having continuously extending side cutting edges straight for a portion of their length and rounded for the remainder, said tip portion 60 further having a transverse straight cutting edge.

3. A dental scaler and curette comprising a blade having an outer flattened and thin portion with an outer curved relatively 65 short terminal tip concave within and convex without provided with rounded widened corners on its convex side, the side edges of said blade and its curved tip portion being provided with continuously extending cutting edges straight for the major portion 70 of their length and curved for the remaining portion, said tip part having a transverse straight cutting edge joining with the rounded 75 corner portions.

4. A dental scaler and curette comprising a handle having a shank and with a laterally bent portion, and a blade extending substantially at right angles to said shank portion, said blade being flattened and thin in one 80 aspect and twisted spirally about its long axis, said blade having a curved tip portion lying substantially in the prolongation of the axis of the handle, said curved tip portion being concave within and convex without and having rounded corner portions on its convex side, said rounded tip portion also having a transverse cutting edge and rounded lateral cutting edges, said blade further having straight cutting edges adjoining said 85 laterally curved cutting edges.

THOMAS F. BATES.
